(74) *Attorney, Agent, or Firm* — Wang Law Firm, Inc.

(57) **CLAIM**

The ornamental design for a silicone scraper, as shown and described.

DESCRIPTION

FIG. 1 is a top front perspective view of a silicone scraper in accordance with the present invention;

FIG. 2 is a top rear perspective view thereof;

FIG. 3 is a bottom front perspective view thereof;

FIG. 4 is a bottom rear view perspective view thereof;

FIG. 5 is a front view thereof;

FIG. 6 is a rear view thereof;

FIG. 7 is a left view thereof;

FIG. 8 is a right view thereof;

FIG. 9 is a top view thereof; and,

FIG. 10 is a bottom view thereof.

1 Claim, 10 Drawing Sheets
